UNITED STATES PATENT OFFICE.

AMOS A. WILCOX AND EVA C. ALDERMAN, OF CLEVELAND, OHIO.

COPY-HOLDER.

SPECIFICATION forming part of Letters Patent No. 553,088, dated January 14, 1896.

Application filed February 1, 1895. Serial No. 536,923. (No model.)

To all whom it may concern:

Be it known that we, AMOS A. WILCOX and EVA C. ALDERMAN, citizens of the United States, residing at Cleveland, county of Cuyahoga, and State of Ohio, have invented certain new and useful Improvements in Copy-Holders, of which the following is a specification, the principle of the invention being herein explained and the best mode in which we have contemplated applying that principle, so as to distinguish it from other inventions.

The annexed drawings and the following description set forth in detail one mechanical form embodying the invention, such detail construction being but one of various mechanical forms in which the principle of the invention may be used.

In said annexed drawings, Figure I represents a perspective view of our improved copy-holder, and Fig. II a front elevation of the same, showing the upright in longitudinal section.

A base A is formed by bending a piece of wire or metal rod into the shape of a circle, and one end of such wire or rod is bent upward and slightly inclined over the base to form a stud a, to which the upright is secured. The upright consists of a straight wire or rod 25 B, to the lower end of which is secured a piece of metal tube forming a socket b, which fits upon the inclined stud of the base. The socket is formed with a longitudinal slot b', open at its lower end, which slot may slide 30 upon a pin a', projecting from the stud, said slot and pin serving to prevent the socket from turning upon the stud. A sleeve C, having a collar c, slides upon the upper portion of the upright and is guided upon the same 35 by longitudinal slots c', sliding upon guide-lugs formed by the ends of a pin b², inserted through the slots and the upright. The upper end of the upright is curved backward, and again forward and downward, to form a hook B', to the end of which a transverse bar 40 is secured, which forms the upper stationary clamping-jaw, B², of the holder. A lower movable jaw, C', is secured upon the ends of two diverging curved arms c², which project upward from the collar of the sliding sleeve upon the upright. Yielding sleeves C², of rubber or similar material, are preferably fitted 45 upon the lower jaw. A coiled spring D fits upon the upright and bears against the upper end of the socket and the lower end of the

sliding sleeve, thus serving to force the latter upward and the movable jaw against the stationary jaw.

While, of course, this copy-holder may be employed for holding any kind of copy-sheets, yet it is particularly adapted to the use of 60 stenographers and typewriter-operators, as it is easily portable when the upright is taken off from the base and the two parts placed flat together, and will form when again put 65 together a convenient support for the stenographic note-books generally used, the upper portion of the leaves of the book being held by the clamp while the book rests at a convenient incline against the inclined upright. 70 The clamp may be easily opened to any reasonable extent by drawing down upon the collar of the sliding sleeve, and the spring will automatically close the jaws.

Other modes of applying the principle of 75 our invention may be employed for the mode herein explained. Change may therefore be made as regards the mechanism thus disclosed, provided the principles of construction set forth, respectively, in the following 80 claims are employed.

We therefore particularly point out and distinctly claim as our invention—

1. In a copy holder, the combination of an upright having a hooked upper end, an upper, 85 stationary clamping jaw secured to the hooked end of the upright, a movable clamping jaw supported by a sleeve sliding upon the upright, and a spring bearing against said sleeve, substantially as set forth.

2. In a copy holder, the combination of a base formed from a circularly bent metal rod having one end bent upward to form an inclined stud, an upright having a socket at its lower end fitted upon said stud and a hooked upper portion, a transverse rod secured to the downwardly bent end of said portion to form a stationary clamping jaw, a sleeve sliding upon the upright, a spring forcing said sleeve upward, and a transverse rod supported from 95 said sleeve to form a movable clamping jaw, substantially as set forth.

In testimony that we claim the foregoing to be our invention we have hereunto set our hands this 29th day of January, A. D. 1895. 105

AMOS A. WILCOX.
EVA C. ALDERMAN.

Witnesses:

WM. SECHER,
DAVID I. DAVIES.
